UNITED STATES PATENT OFFICE.

WALDO C. BRYANT, OF BRIDGEPORT, CONNECTICUT, ASSIGNOR TO THE BRYANT ELECTRIC COMPANY, OF SAME PLACE.

DESIGN FOR AN ELECTRIC CONTACT-BUTTON.

SPECIFICATION forming part of Design No. 31,147, dated July 4, 1899.

Application filed June 7, 1899. Serial No. 719,716. Term of patent 7 years.

To all whom it may concern:

Be it known that I, WALDO C. BRYANT, a citizen of the United States of America, residing in Bridgeport, county of Fairfield, Connecticut, have invented a Design for an Electrical Contact-Button, of which the following is a specification.

My design for a contact-button is shown in the accompanying drawings, in which—

10 Figures 1 and 3 are views of the opposite faces of the button, and Fig. 2 is a cross-section.

The button A is circular, with beveled edges a a', a single central opening and an enlarged concave or cup-shaped recess a² at one 15 face, a tubular piece B, passing through the central opening, a flange b in the recess, and

an umbrella-like flange b' on the face of the button, opposite the recess a'.

The essential features of my design are a 20 circular button with a central opening, cup-shaped recess a², and tubular piece B, with its two flanges.

I claim as my invention—

The design for a contact-button herein 25 shown and described.

In testimony whereof I have signed my name to this specification in the presence of two subscribing witnesses.

WALDO C. BRYANT.
